HAND BAG FASTENER

Frank J. Quigan, Jackson Heights, N. Y., assignor
to Frank J. Quigan Company, Inc., a corpora-
tion of New York

Application November 6, 1930. Serial No. 493,745

5 Claims. (Cl. 292—204)

This invention relates to handbags and has for its general object and purpose to provide a simply constructed, novel, and ornamental latching means for the hingedly connected frame parts of the handbag.

More particularly, it is the object of my invention to provide a new latching means particularly designed for use in connection with the inverted channel type of handbag frame which, in addition to adding to the ornamental appearance of the bag as a whole, may be easily and quickly operated to securely latch the frame parts in closed face to face contact, or permit the same to be easily moved relatively to each other to open 15 position affording access to the contents of the bag.

It is a further object of my invention to provide a device of the above character, which will be capable of manufacture at comparatively small 20 cost, exceedingly strong and durable in its construction, and in which the cooperating parts are so mounted and arranged that accidental release of the latch means and opening of the bag is substantially prevented. With the above and other 25 objects in view, the invention consists in the improved handbag and latching means therefor and in the form, construction, and relative arrangement of its several parts as will be hereinafter described, illustrated in the accompanying drawing, and subsequently incorporated in the subjoined claims.

In the drawing wherein I have disclosed one simple, practical embodiment of my invention, and wherein similar reference characters designate corresponding parts throughout the several views:—

Figure 1 is a fragmentary side elevation, certain parts being shown in section illustrating one embodiment of the present invention;

40 Fig. 2 is a top plan view;

Fig. 3 is a vertical sectional view on an enlarged scale taken on the line 3—3 of Fig. 1;

Fig. 4 is an enlarged detail elevation illustrating the mounting of the movable latch part upon 45 one of the frame members; and

Fig. 5 is a fragmentary perspective view showing the frame parts separated.

Referring in detail to the drawing, for purposes of illustration, I have shown my invention as 50 applied to a bag frame now generally referred to as of the inverted channel type, in which each of the bag frame members designated 5 and 6, respectively, is in the form of an inverted U-shaped sheet metal strip, said metal strips being bent at 55 spaced points to provide a bag frame member of

the desired pre-determined shape. These frame members at their corresponding ends are hingedly connected together as indicated at 7. Throughout the length of each frame member, the channel thereof opens outwardly. Within these channels, 60 the upper and side edges of the flexible bag or pouch material 8, which extends over the outer side walls of the respective frame members, are engaged, and securely held by clinching the walls of the frame members thereon. 65

For the purpose of releasably latching the frame members 5 and 6 together with their inner walls in face to face contact so as to thereby securely close the bag, I mount upon the inner flange or wall of the top portion of each frame 70 member a longitudinally extending plate indicated at 9 and 10 respectively. These plates may be of any desired ornamental form, and have their lower portions reduced in thickness as indicated at 11 to extend downwardly upon the inner side 75 of the inner flange of the respective frame members, said reduced portions of the plate providing the longitudinally extending shoulders 12 seating closely upon the upper edges of said frame flanges, while the inner face of the plate is disposed in the same plane as the inner face of the frame flange. The parts 12 of the plates are 80 welded or otherwise permanently secured to the frame flanges. Thus when the two frames are brought together in closed position, the opposed 85 surfaces of the plates 9 and 10, as well as the opposed surfaces of the inner flanges of the frame members 5 and 6 respectively will be in face to face contact.

As herein shown, the plate 9 carried by the 90 frame member 6 is provided in the outer face thereof with a recess 13 which receives an annular washer plate 14 secured upon the reduced end 16 of the stud 15 projecting from one side of the latch member 17. The washer plate 14 has an 95 eccentric portion indicated at 14' which is adapted to frictionally bind upon the circumferential wall of the recess 13 at opposite ends of the eccentrically curved portion 13' of said wall. Thus rotative movement of the latch member 17 in 100 each direction will be limited. This feature, however, is of secondary importance, and may, if desired, be eliminated.

The plate 10 on the other frame member 5, as 105 herein shown, is provided with a central opening 18 therethrough corresponding in its general shape or contour to the shape of the latch member 17, and at opposite sides of this central opening the additional ornamental openings 19 are formed through said plate, while corresponding 110

openings 20 are likewise formed in the other plate 9 at each side of the latch member 17.

In the form of my invention as herein shown, the opening 18 and the latch member 17 are of polygonal shape, preferably of diamond shape form. In order to latch the bag frame members in closed position, the member 17 is first turned to position its longer axis horizontally or parallel with the top of the frame member as shown in Fig. 5. The two frame members and the plates 9 and 10 are then brought together in face to face contact with each other, the latch member 17 passing freely through the opening 18. Said latch member is then turned through an angle of 90° so as to position its longer axis vertically and dispose the ends of said diamond-shaped latch member in engagement with the surface of the plate 10 above and below the opening 18 therein. As the latch member is moved to this position the periphery of the washer plate 14 frictionally binds against the edge wall of the recess 13 in the plate 9, which tends to prevent the accidental or unintentional turning movement of the latch member 17 to a position in longitudinal alignment with the opening 18, so that the two frame members might become separated. When the member 17 is in its latching position, as shown in Fig. 3, the two frame members and the plates 9 and 10 are securely latched substantially throughout their length in face to face contact with each other.

From the foregoing description considered in connection with the accompanying drawing, the construction and manner of operation of my present invention will be clearly and fully understood. It will be seen that I have devised an improved latch means for handbags and the like, which is simple and very durable in its construction, may be easily and quickly operated and may be produced in various shapes or forms to materially enhance the ornamental appearance of the bag without greatly increasing the manufacturing cost thereof. While I have herein shown and described an embodiment of my invention, which has been found entirely satisfactory in practical use, nevertheless it is to be understood that the essential features thereof may also be produced in various other detailed forms, and, I, therefore, reserve the privilege of all such legitimate changes as may be fairly embodied within the spirit and scope of the invention as claimed.

I claim:—

1. A fastener for a handbag of the type having pivotally hinged frame members with the inner walls of the frame members in adjacent relation when the frame is closed; said fastener comprising a pair of plates projecting upwardly one from each of said frame members, and arranged to lie in face to face relation when the frame members are closed, one of said plates having an opening therein, a pivoted member carried by the second of said plates adapted to pass through said opening in one of its positions and to not pass through said opening in another of its positions, said member and the plate pivotally carrying it com-

prising relatively movable engaging means adapted to wedgingly engage with one another to stop and frictionally retain said member at each of its said positions until forcefully disengaged therefrom while allowing it free movement therebetween, the turning of said member until stopped and wedgingly retained in its first mentioned position insuring alignment of it to pass through said opening and subsequent disengagement of said member from said first position and turning thereof until stopped and wedgingly retained in said other position insuring location and securement thereof in a position to not pass through said opening, irrespective of any coaction or lack of coaction between said member and the edges of said opening.

2. A fastener for a handbag of the type having pivotally hinged frame members with the inner walls of the frame members in adjacent relation when the frame is closed; said fastener comprising a pair of plates projecting one from each of said frame members, one of said plates having an opening therein, a pivoted latch means carried by the second of said plates and adapted to pass through said opening in one of its positions and to not pass through said opening in another of its positions, said latch means including means adapted to jam at each of said positions but to move freely therebetween, the turning of said latch means to jam in its first mentioned position insuring alignment of it to pass through said opening and the subsequent turning of said latch means to jam in its other position insuring location and securement thereof in a position to not pass through said opening, irrespective of any coaction or lack of coaction between said latch means and the edges of said opening.

3. A fastener according to claim 2, in which the pivoted latch means and the plate carrying the same present substantially rigid cooperating elements which wedgingly engage with one another in each of the aforesaid positions of the pivoted latch means, to effect the jamming of the same.

4. A fastener according to claim 2, in which the pivoted latch means is provided with an eccentric washer rigid therewith, and in which the plate carrying the same is provided with two substantially rigid abutment surfaces adjacent said eccentric washer, which are wedgingly engaged thereby, one in each of the aforesaid positions of the pivoted latch means, to effect the jamming of the same.

5. A fastener according to claim 2, in which the pivoted latch means is provided with an eccentric washer rigid therewith, and in which the plate carrying the same is provided with an eccentric counter-bore in which said eccentric washer lies, said eccentric washer and counter-bore being proportioned to wedgingly jam with one another in each of the aforesaid positions of the pivoted latch means, to effect the jamming of the same.

FRANK J. QUIGAN.
